WALL LIGHTING FIXTURE OR SIMILAR ARTICLE

Joseph L. Jaffe, Jr., Shaker Heights, Ohio, assignor to
The Perfectlite Company, Cleveland, Ohio, a corporation of Ohio

Filed Nov. 18, 1959, Ser. No. 58,383

Term of patent 7 years

(Cl. D48—4)

FIG. 1

FIG. 5

Fig. 1 is a perspective view of a wall lighting fixture or similar article showing my new design;

Fig. 2 is a front elevational view thereof;

Fig. 3 is an end elevational view thereof;

Fig. 4 is a top plan view thereof; and

Fig. 5 is a bottom plan view.

The end of the fixture not shown is the same as the end illustrated.

I claim:

The ornamental design for a wall lighting fixture or similar article, as shown and described.
